US00D866740S

(12) **United States Design Patent** (10) Patent No.: **US D866,740 S**
Reinhard et al. (45) Date of Patent: **** Nov. 12, 2019**

(54) **FILTER**

(71) Applicant: **STEP-TEC AG**, Luterbach (CH)

(72) Inventors: **Edwin Reinhard**, Niederönz (CH);
Gianni Fazzone, Fulenbach (CH)

(73) Assignee: **STEP-TEC AG**, Luterbach (CH)

(**) Term: **15 Years**

(21) Appl. No.: **35/505,129**

(22) Filed: **Feb. 26, 2018**

(80) **Hague Agreement Data**

Int. Filing Date: **Dec. 1, 2017**

Int. Reg. No.: **DM/099994**

Int. Reg. Date: **Feb. 26, 2018**

Int. Reg. Pub. Date: **Jun. 15, 2018**
